CLAIM

The ornamental design for a bathing implement, as shown and described.

DESCRIPTION

FIG. 1 is a front perspective view of a bathing implement showing our new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The constant broken lines shown on the top of the implement in FIG. 1 and the bottom of the implement in FIG. 7 represent the bounds of the claim. The broken lines showing a hanging loop and a scrubbing member in FIG. 1 represent environmental structure and the broken lines shown about the implement in FIGS. 1-6 illustrate portions thereof that along with all of the other broken lines form no part of the claimed design.
